UNITED STATES PATENT OFFICE.

ELMER D. SMYSER, OF FELLOWS, CALIFORNIA.

TEMPERATURE REGULATOR.

Application filed November 5, 1923. Serial No. 672,988.

To all whom it may concern:

Be it known that I, ELMER D. SMYSER, a citizen of the United States, residing at Fellows, in the county of Kern and State of California, have invented new and useful Improvements in Temperature Regulators, of which the following is a specification.

This invention relates to an improved means for automatically regulating the temperature of burner heated furnaces, boilers and ovens.

An object of the invention is to provide a device of the character described which may be quickly and easily attached and set for 15 operation at predetermined temperatures on various forms of burner heated furnaces, ovens, boilers and the like.

Another object of the invention is to provide a novel temperature regulator for 20 boilers which combines with it a steam pressure regulating means, both of which work cooperatively for the purpose of maintaining an even predetermined steam pressure in the boiler and for preventing boiler 25 explosions, both by controlling the burner valve.

With the above mentioned and other objects in view, the invention consists in the novel construction and combination of parts 30 hereinafter described, illustrated in the accompanying drawings, and set forth in the claims hereto appended, it being understood that various changes in the form, proportion, size and minor details of construction 35 within the scope of the claims may be resorted to without departing from the spirit or sacrificing any of the advantages of the invention.

Referring to the drawings:

The figure is a top plan view partly in section of the apparatus of the invention as when adapted for use in connection with a boiler.

Referring to the drawing there is shown a 45 boiler 24 which is heated by a burner 25 having a valve 26 which is closed against the action of a spring 27. To the valve 26 is connected a rod 28 which is in turn connected with a bell crank 29 mounted on an angular arm 30 which is fixed as at 31 to one side of the boiler, near one end thereof. To the bell crank 29 is connected one end of 50 an operating rod 32 which rod is extended through a steam pressure regulating chamber 33, which chamber is supported by an

arm 34 fixed to the outer side of the boiler near the other end thereof. Extending from the boiler is a pipe 35 which supplies steam to the chamber 33 through a port 36 provided intermediate the ends of said chamber. A piston 37 is mounted within the chamber 33 and fixed to the rod 32. The outer end of the rod 32 which is extended beyond the chamber 33 has one end of a bell crank 38 pivoted thereto, said crank being pivoted intermediate of its ends as at 39 to a bracket 40 carried by the chamber. One leg of this bell crank has a weight 41 adjustably mounted thereon and arranged so that the weight will work against the 70 pressure of the steam in the chamber. On opposite sides of the end wall 42 of the chamber are stop members 43 and 44 which are fixed to the rod 32 and are adapted to engage with said wall 42 on expansion 75 and contraction of the boiler and consequent movement of the parts carried by the boiler. The rod 32 is made in two sections, the opposed ends of which are threaded into a turn buckle 46 which has a hand wheel 47 80 embodied therein and serves as a throttle for operating the valve.

Assuming that it is desirable to maintain an even steam pressure in the boiler, when the boiler begins to function the operator 85 may open and close the burner valve and vary the intensity of the heat by adjusting the wheel 47 on the turn buckle 46, the mechanism then serving as a throttle control. When the desired pressure of steam is 90 produced, for example 400 lbs., the operator adjusts the weight 41 so that the leverage exerted through the bell crank 38 is sufficient to hold the piston 37 in a definite position against the pressure of steam behind 95 the piston in said chamber 33, the steam having entered the chamber through the pipe 35, the mechanism is then set for operation. If the steam pressure increases beyond the 100 balance point, the force of the weight is overcome and the piston 37 is moved so as to pull on the rod 32, rock the bell crank 29 and pull on the rod 28 so as to close the valve, thereby shutting down the burner so that less heat is produced in accordance with 105 the closing movement of the valve, and less steam is generated. This tends to maintain an even pressure. When the steam pressure is increased, the heat of the boiler is increased and said boiler expands in the direc- 110

tion of its length, causing the arms 30 and 34 to move in opposite directions away from one another and producing movement of the rod 32. On such movement of the arm 34, the chamber 33 is moved and the wall 42 of the chamber engages the stop 44 thereby pulling on the rod 32. As the arm 30 moves in the opposite direction to the movement of the arm 34, the tendency is to move the bell crank bodily but since the rod 32 tends to rock the bell crank and move it in the opposite direction, said bell crank is rocked by movement of the arm 30 and fulcrums on its pivot connection with the rod 32. Thus, both movements of the arms cause the rods 32 and 28 to be pulled in the same direction and to close the valve.

When the steam pressure decreases the weight 41 moves the piston 37 in the opposite direction so as to push on the rod 32 and this reverses the movement of the parts causing the valve to open, which opening movement is assisted by the action of the spring 27 thereby providing greater burner heat in the furnace and producing more steam so as to as quickly as possible increase and maintain the desired steam pressure. The contraction of the boiler assists in this movement and assures an accurate and reliable automatic operation.

If the water in the boiler reaches a dangerously low level, the heat of the boiler increases so as to cause considerable expansion as previously described. On this expansion of the boiler, the rods 32 and 28 are pulled and cause the burner valve to immediately close thereby shutting off the generation of steam and preventing explosion or other damage to the boiler. Of course, on the increased steam pressure due to the low water supply, the mechanism will act as previously described to cut off the valve as well as through the expansion action of the boiler itself.

The rods and other elements of the mechanism which constitute the means of connection between the brackets that are attached to the expandible and contractible elements and the valve are formed of material

which does not appreciably expand and contract. 50

I claim:

1. A device of the character described in combination with burner heated apparatus including a valve for controlling the burner and a container for a fluid which is heated by the burner, which container is subject to expansion and contraction, means of connection between the container and valve providing for closing and opening of the valve 55 on expansion and contraction of said container and means acting coincident to variation in the pressure of the fluid in said container to operate said means of connection and open and close the valve. 60

2. In a device of the character described the combination with burner heated apparatus including a valve for controlling the burner and a container for fluid, which container is heated by the burner and is subject 70 to expansion and contraction, means of connection between the burner valve and said container providing for closing and opening of said valve on contraction and expansion of said container and means associated with said means of connection and said container for actuating the valve through said means of connection when the pressure in the container drops below or exceeds a predetermined point. 75

3. In a device of the character described the combination with burner heated apparatus including a valve for controlling the burner and a container for fluid, which container is heated by the burner and is subject 85 to expansion and contraction, means of connection between the burner valve and said container providing for closing and opening of said valve on contraction and expansion of said container and means associated with said means of connection and said container for actuating the valve through said means of connection when the pressure in the container drops below or exceeds a predetermined point, which means of connection is 90 adjustable to provide for its operation at different pressures. 95
